Primary Examiner—James Gandy**Assistant Examiner—Carol Rademaker****Attorney, Agent, or Firm—Wood, Herron & Evans, LLP****[57] CLAIM**

The ornamental design for a collapsible container body, as shown and described.

DESCRIPTION

FIG. 1 is a front view of an ornamental design for the body of a collapsible container in accordance with the invention, with the back view being a mirror image thereof; FIG. 2 is a side view thereof, with the opposite side being a mirror image;

FIG. 3 is a top plan view thereof;

FIG. 4 is a bottom plan view thereof;

FIG. 5 is a cross-sectional view thereof taken along line 5—5 of FIG. 1;

FIG. 6 is a cross-sectional view thereof taken along line 6—6 of FIG. 2; and,

FIG. 7 is a top isometric view thereof.

The phantom line depiction of the neck of a container incorporating the collapsible container body of the invention depicts the environment of the invention and forms no part thereof.
